(57) **CLAIM**

The ornamental design for a portion of a watch, as shown and described.

DESCRIPTION

FIG. 1 is a top plan view of a portion of a watch showing my new design;

FIG. 2 is a side elevational view of one side thereof;
FIG. 3 is a side elevational view of another side thereof
opposite that of FIG. 2;

FIG. 4 is an end elevational view of one end thereof;
FIG. 5 is an end elevational view of another end thereof
opposite that of FIG. 4; and,
FIG. 6 is a perspective view thereof.

The broken line showing of the remainder of the watch
including the bottom and the band is for illustrative purposes
only and forms no part of the claimed design.

1 Claim, 2 Drawing Sheets

FIG. 6
